UNITED STATES PATENT OFFICE.

LAWRENCE S. TAYLOR, OF NACOGDOCHES, TEXAS.

WOOD-SPLITTING MACHINE.

1,278,397.

Specification of Letters Patent. Patented Sept. 10, 1918.

Application filed March 28, 1918. Serial No. 225,296.

To all whom it may concern:

Be it known that I, LAWRENCE S. TAYLOR, a citizen of the United States, residing at Nacogdoches, in the county of Nacogdoches, and State of Texas, have invented certain new and useful Improvements in Wood-Splitting Machines; and I do declare the following to be a full, clear, and exact description of the invention, such as will enable others skilled in the art to which it appertains to make and use the same.

This invention relates to wood splitting machines, and especially to certain improvements on the machine which constitutes the subject matter of Patent No. 800,512 issued to me on September 26, 1905.

One object of the invention is to provide means whereby the billet or stick of wood to be split is positioned in the path of the maul or hammer after it had been placed on the splitting blade or blades preparatory to being moved into the path of the hammer.

Another object of the invention is to provide for effectually preventing rebounding or retrograde movement of the billet carrier.

Other objects and advantages may become apparent to persons who read the following details of construction in connection with the accompanying drawings in which:

Figure 1 is a fragmental vertical sectional view showing the billet carrier in position for receiving the billet;

Fig. 2 is a fragmental vertical section showing the billet carrier in position to hold the billet in the path of the striker or hammer;

Fig. 3 is a top plan view, parts being broken away so as to show other parts more clearly; and,

Fig. 4 is a perspective view partly in section and partly broken away.

Referring to these drawings in detail, in which similar reference characters correspond with similar parts throughout the several views, the parts that are shown in the drawings but not bearing a reference character are substantially the same as described in my patent previously referred to, while other parts are referred to by letters of the alphabet merely for the sake of definitely showing the relation of parts that constitute the subject matter of this invention.

Upon the frame structure A is supported a rotor or drum E which carries a maul or

hammer F. The rotor may be rotated by any appropriate means in the direction of the arrow thereon, and in thus rotating, the hammer F is moved downward in the direction of the splitting blade or blades S so as to press a billet of wood upon the blades with sufficient force to split said billet. However, it is desirable to first place the billet in the preparatory position shown in Fig. 1, so as to avoid accidents which might occur if the hammer F should strike the billet while being placed on the blades. Moreover, it is desirable that the billet be moved from its preparatory position (see Fig. 1) to its final position (see Fig. 2), and that such movement be effected automatically by the rotation of the rotor E. For accomplishing this result, I provide the rotor with a lug or cam 5, and I provide the carrier O with a rod 6 which is slidable longitudinally through an opening or tangential bore 6'. The rod 6 is preferably formed of spring steel and is primarily slightly curved, and is forced into the rectilinear opening 6', so that the surface around said opening frictionally engages the lateral sides of the rod 6 so as to yieldingly retain the rod in any position to which it may be set. However, by tapping the rod with a hammer or mallet on its upper end, it may be instantly thrust downward into the path of the cam 5, which latter will strike the lower end of the rod 6 and coöperate therewith for rocking the carrier O upon the track provided therefor. It will be understood from said prior patent that means are provided for preventing the carrier O from sliding on the track while rocking on the latter; and it will also be understood that the bar or stop V coöperates with the carrier O for supporting the blades S and T in the position for supporting the billet in the path of the hammer F. However, it has been ascertained that there is a tendency for the blades to rebound after striking the anvil V, and in order to offset such tendency, I provide means for detaining the carrier O in its preparatory position and also in its operative position, such means being now described in detail as follows:

A segmental detaining element 7 is secured on the carrier O by appropriate means, as shown at 8, and this member 7 is provided with an upper depression 9, a lower depression 10 and a groove 11 connecting these depressions. A pawl or second detaining element 12 is provided with a lug 13

which fits interchangeably in the depressions 9 and 10 and is adapted to slide through the groove 11. The member 12 is pivotally mounted at 14 upon a bracket 15, and a 5 spring 16 connects the bracket with the pawl 12. It will be seen, therefore, that the detaining elements 7 and 12 coöperate to hold the carrier alternately in its preparatory position (shown in Fig. 1) and its final or 10 operative position (shown in Fig. 2.)

The operation is as follows:

The operator causes the rotor E to rotate in the direction of the arrow thereon, and this rotor being relatively heavy and rotating 15 at a high speed, the hammer F is adapted to exert sufficient force to drive the billet against the blades S and T with sufficient pressure to split the billet, as set forth in the said prior patent. The carrier O is disposed as shown in Fig. 1, and the billet is positioned preparatory to being moved into the path of the hammer, and the rod 6 is out of the way of the cam 5; the operator now taps the rod 6 on its upper end and 20 drives it downwardly into the path of the cam 5, whereupon the cam strikes the rod 6 and rocks the carriage O into the position illustrated in Fig. 2. In order to thus rock the carriage O, the lug 13 and depression 9 25 are of such shape that the carrier is only yieldingly detained thereby; or, in other words, the elements 9 and 13 are yieldingly engaged with one another, so that a forward pressure on the top of the carriage 9 will 30 cause the disengagement of these detaining elements and allow the carrier O to rock forward into its operative position. Therefore, when the billet is dropped upon the splitting blade or blades, the handle W may be 35 grasped for offsetting the tendency of the billet to move the carriage forward, and this handle may also be grasped for returning the carriage to its inward or preparatory position.

40 By the improvements set forth in the foregoing, it will be seen that I obtain the maximum efficiency by assuring that the billet is set to receive the full effect of the hammer's stroke at each operation; whereas, the billet 45 has previously been positioned entirely by manual movement of the carrier O, and in thus moving the carrier, it was found that the hammer sometimes only struck the edge of the billet, not exerting sufficient force to 50 cause the splitting thereof, but causing the hammer to be chocked by the billet, and thus necessitating a very considerable loss of time in reversing movement of the rotor, removing the billet and replacing it in a different 55 position. It will be seen, therefore, that I 60 have invented improvements of very considerable importance, and it is believed that such improvements will result in the great commercial success of this form of wood 65 splitting machine.

Although I have described this embodiment of my invention in minute detail, it is to be understood that I do not limit my invention to these exact details of construction and arrangement of parts but I am entitled 70 to make such minor changes that do not constitute a departure from the appended claims.

I claim:

1. In a splitting machine, the combination 75 of a hammer, means for moving said hammer downward in a predetermined path for striking a billet, a blade supporting at least in part said billet and movable therewith into and out of the path of said hammer, 80 and means operated by the first named means for so moving said blade, substantially as specified.
2. In a splitting machine, the combination 85 of a hammer, means for moving said hammer downward in a predetermined path for striking the billet, a blade supporting at least in part said billet, and movable therewith into and out of the path of said hammer, 90 and means carried by the first named means for so moving said blade.
3. In a splitting machine, the combination 95 of a hammer, means for moving said hammer downward in a predetermined path for striking a billet, a blade supporting at least in part said billet and movable therewith into and out of the path of said hammer, 100 and means for preventing retrograde movement of the said blade from its position in which it supports the billet in the path of the hammer, the function of the last named means being irrespective of the operation of the first named means.
4. In a splitting machine, the combination 105 of a hammer, means for moving said hammer along a predetermined path, a blade, a carrier coöoperative with said blade for receiving a billet and supporting the latter in its preparatory position out of the path of said hammer, means supported by said carrier and coöoperative with the first said means for moving the billet from its preparatory position into its final position in the path of said hammer, and detaining means for holding the said carrier alternately in the positions for supporting the billet in said preparatory position and in said final position these functions of the last named means being irrespective of the operation of the first 110 named means.
5. In combination, a rotor, a hammer and a cam carried thereby, a rocking carrier, a blade carried by the carrier and coöoperative therewith to receive a billet in a preparatory position out of the path of said hammer, and means carried by said rocking carrier and coöoperative with said cam for rocking said carrier so as to bring the billet into the path of said hammer.
6. In combination, a rotor, a hammer and 115

120 125 130

- a cam carried thereby, a rocking carrier, a blade carried by the carrier and coöperative therewith to receive a billet in a preparatory position out of the path of said hammer, and
5 means carried by said rocking carrier and movable with relation to the latter into co-operation with said cam for effecting such rocking movement of said carrier as to move the billet into the path of said hammer.
- 10 7. In combination, a rotor, a hammer and a cam carried thereby, a rocking carrier, a blade carried by the carrier and coöperative therewith to receive a billet in a preparatory position out of the path of said hammer, and

a rod carried by said rocking carrier and 15 yieldingly detained against movement relative to the latter but movable longitudinally into such coöperative relation with said cam as to effect a rocking movement of said carrier and thereby move the billet into the 20 path of said hammer.

In testimony whereof I have hereunto set my hand in the presence of two subscribing witnesses.

LAWRENCE S. TAYLOR.
